UNITED STATES PATENT OFFICE.

JOHN H. MCKINNEY, OF SHREVEPORT, LOUISIANA.

FREEZER.

No. 850,442.

Specification of Letters Patent.

Patented April 16, 1907.

Application filed August 29, 1905. Serial No. 276,278.

To all whom it may concern:

Be it known that I, JOHN H. MCKINNEY, a citizen of the United States, residing at Shreveport, in the parish of Caddo and State 5 of Louisiana, have invented a new and useful Freezer, of which the following is a specification.

This invention relates to ice-cream freezers; and its object is to provide a simple form 10 of freezer in which may be placed a large number of ice-cream holders of different sizes and shapes, said holders being adapted to contain ice-cream of the same or of different kinds.

15 A still further object is to provide a freezer which is so constructed as to quickly solidify the contents of the holders and which has novel means for preventing the admission of heat to the compartment containing the 20 holders.

With these and other objects in view the invention consists of certain novel features of construction and combinations of parts, which will be hereinafter more fully de- 25 scribed, and pointed out in the claim.

In the accompanying drawings is shown the preferred form of the invention.

In said drawings, Figure 1 is a view, partly in section and partly in side elevation, 30 of a freezer constructed in accordance with the present invention; and Fig. 2 is a section on line 2 2, Fig. 1.

Referring to the figures by characters of reference, 23 designates supporting-stands suitably connected and upon which are journaled trunnions 22 and 22', which are secured in any suitable manner to the polygonal heads 20 of an outer polygonal casing 16. One of the faces of this casing is formed 40 by a door 17, which is hinged, as at 18, and is adapted to be fastened in closed position by means of any suitable lock, such as disclosed at 19. Secured upon the inner faces of the heads 20 are polygonal heads 11, the 45 edges of these heads 11 being parallel with and at equal distances from the edges of the heads 20. The heads 11 are surrounded by an inner polygonal casing 10, one face of which is formed by a door 12, which is hinged, 50 as at 13, and adapted to be secured in place by means of a suitable lock 14. The door 12 is disposed directly inside the door of the outer casing, so that by opening the outer door 17 access may be easily had to the inner 55 door, which inner door is capable of being swung open into the door-opening in the

outer casing. The inner and outer casings form a continuous annular ice-compartment therearound, and which extends uninterruptedly throughout the length of the two casings. Access to all portions of this compartment may be had by simply opening the outer door 17, whereupon ice may be easily packed within the annular compartment, so as to completely surround the inner casing 60 10. The walls of this annular compartment are completely covered with suitable heat-excluding material, as shown at 21, and the inner compartment formed within the casing 10 is also lined throughout with a suitable 65 15 heat-excluding material 15. A crank 24 is connected to the trunnion 22' to facilitate the manual rotation of the entire freezer.

In using the freezer herein described the same is rotated until the doors 17 and 12 are 70 uppermost, whereupon the two doors are opened and a quantity of ice mixed with salt is placed within the inner casing 10. Ice-cream molds or receptacles 25, which may be of any desired sizes and shapes, are then 75 packed within the ice in the casing 10, after which said casing is entirely filled with ice and the door 12 closed and locked. A mixture of ice and salt is then tightly packed within the annular compartment formed by 80 the outer casing 16, and after this compartment has been filled the outer door 17 is closed and locked. The freezer can then be rotated, so as to cause agitation of the ice and any ice-water which might be produced 85 therein, and after the molds 25 have been within the freezer for a predetermined period said freezer is moved in position with its doors uppermost and the upper door 17 is opened and the ice covering the door 12 is 90 removed. Said door 12 is then also opened and the ice and molds within the inner compartment removed. An additional supply 95 of ice and molds can then be placed in the inner compartment, if desired. Should the 100 operator wish to remove all of the contents of the freezer, it is merely necessary to open the two doors 12 and 17 and turn the freezer until said doors are in their lowest position, whereupon the ice, &c., will slide by gravity 105 out of both compartments of the freezer. By providing casings which are shaped as shown and with walls inclined toward the door-openings said inclined walls constitute hoppers for directing all of the contents of the 110 compartments toward the openings when the freezer is inverted.

2
What is claimed is—

In an ice-cream freezer the combination with supports; of an outer polygonal casing, a door constituting one wall of the casing, 5 those walls of said casing adjoining the door being inclined toward the door to constitute a hopper when the casing is inverted, trunnions extending from the ends of the casing and journaled on the supports, polygonal 10 heads secured upon the inner faces of the ends of the outer casing, an inner casing secured upon and surrounding said heads to form an inner casing concentric with the outer casing, there being an outer annular compartment around the inner casing, said annular compartment extending uninterrupt- 15

edly throughout the length of the inner compartment, a door constituting one wall of the inner casing and disposed adjacent the inner face of the door of the outer casing, two walls 20 of the inner casing being inclined toward the door-opening in said casing to form a hopper when the casing is inverted, and means for rotating the casings simultaneously to invert them. 25

In testimony that I claim the foregoing as my own I have hereto affixed my signature in the presence of two witnesses.

JOHN H. MCKINNEY.
